UNITED STATES PATENT OFFICE.

ARTHUR W. PUDDINGTON, OF PROVIDENCE, RHODE ISLAND, ASSIGNOR TO FURNACE IMPROVEMENT COMPANY, OF PROVIDENCE, RHODE ISLAND, A CORPORATION OF RHODE ISLAND.

DAMPER-CONTROLLING MECHANISM FOR FURNACES.

Application filed February 25, 1924. Serial No. 694,913.

To all whom it may concern:

Be it known that I, ARTHUR W. PUDDINGTON, a citizen of the United States, residing at Providence, in the county of Providence and State of Rhode Island, have invented certain new and useful Improvements in Damper-Controlling Mechanism for Furnaces, of which the following is a specification.

10 This invention relates to damper-controlling mechanism for furnaces; and has for its object to provide a mechanism of this character which is an improvement over that disclosed in my prior Patent No. 15 866,515, of September 17, 1907, the present invention comprising a valve for controlling the supply of combustible fluid to the furnace in combination with one or more movable elements arranged to be actuated by 20 fluid pressure to open and close this valve which controls the fluid supply to the furnace.

A further object of the invention is the provision of means whereby this valve is 25 operated to control the admission of air to the furnace and also to admit steam if required while the fire door is open and for a further predetermined period after the door is closed.

30 With these and other objects in view, the invention consists of certain novel features of construction, as will be more fully described, and particularly pointed out in the appended claims.

35 In the accompanying drawings.

Figure 1 is a front elevation of a furnace to which my improved fuel supply controlling mechanism is attached.

Figure 2 is a sectional elevation of the 40 chamber which is controlled in its action by fluid pressure.

Figure 3 is a section on line 3—3 of Figure 1 through the air supply conduit and showing the ejector nozzles as forcing the 45 air from the conduit into the furnace.

Figure 4 is a sectional elevation of the cylinder which carries the valve closing pressure and the means for connecting the steam supply valve to the cylinder to be 50 operated through the action of two diaphragms having different exposed areas.

Figure 5 is a sectional elevation of the pressure relief valve arranged to be opened by the opening of the furnace door to relieve the valve closing pressure in the cylinder. 55

It is found in the practical operation of furnaces of this character, of advantage to supply combustible fuel thereto during and for a predetermined period after the operation of stoking the same for the purpose of supplying to the excess of unconsumed carbon then present, the amount of air or of steam and air necessary to insure the burning of such fuel without development of smoke; and to accomplish this I have provided a supply control valve, the movable member of which is operated by a pair of movable elements such as diaphragms or other pressure operating devices each of which may be provided if desired, with a 60 different exposed or effective area, the mechanism being so arranged that the opening of the furnace door may be caused to relieve the pressure beneath one of the diaphragms permitting the pressure of the supplying 65 fluid to act upon the other diaphragm to open the valve and after the door has again been closed the pressure is caused to rise slowly beneath the larger diaphragm forcing the valve closure member to its seat and by 70 my improved construction the valve stem is entirely inclosed or submerged in the pressure thus eliminating the use of packing glands about the stem and so positively preventing leakage around the same; and the 75 following is a detailed description of one means by which these advantageous results may be accomplished:—

With reference to the drawings, 10 designates a furnace the same being provided 80 with the usual fire doors 11 above which is shown as being located a plurality of air injectors 12 comprising elongated nozzles entering openings 13 leading from the main air supply conduit 14 into the firebox of 85 the furnace. The supply of air to this conduit is controlled by a damper 15 which is provided with a plurality of shutters 16 pivoted at 17 and connected together by a bar 18 all to be operated simultaneously by 90 a movement of the knee lever 19. This knee lever is pivoted at 20 and its

upper end 21 is connected to a rod 22 which is pivoted at its upper end at 23. The pin 24 is mounted upon the diaphragm 25 to act upon the under side of this rod just below its pivot point whereby when the diaphragm is pressed outwardly the rod is moved into position shown in dotted lines to swing the shutters to open position.

This shutter-operating diaphragm is controlled in its action by steam pressure admitted through valve 29 from any suitable source of energy (not shown) through pipe 26 and automatic control valve 27 and the steam from this same supply may also be conducted through pipe 28 to communicate with the steam jets 12 or to any other suitable means for forcing air into the furnace or this supply may be shut off entirely if desired by valve 58 permitting the air to be admitted to the furnace through the damper 15 without the intermixing or forcing action of steam.

As it is found in practice of advantage to admit air and sometimes a mixture of air and steam to the combustion chamber of the boiler in order to cause a more complete combustion therein during the distillation of volatile combustible from the freshly stoked fuel, and in order to admit this supply of air or the combined supply of air and steam automatically when the door of the furnace is open for stoking, I have provided a steam pressure supply control cylinder 30 having a dome-shaped head 31 with a threaded neck portion 32 onto which the neck 33 of the inverted valve is screwed.

Just beneath this head is a diaphragm 34 formed of any suitable flexible material and beneath this diaphragm is an intermediate plate 35 arranged to support the diaphragm and leave but a relatively small portion exposed and unsupported to be moved vertically by action of pressure and between this intermediate plate 35 and the flange 36 of the cylinder head, I have mounted a diaphragm 37 which has an exposed area greater than the smaller diaphragm 34 and both this head 30, the two diaphragms, and the intermediate plate 35 are all secured to the flanged end of the cylinder by means of bolts 38.

These two diaphragms are connected together through the bolts 39 and 40 to move in unison with each other.

The valve member carrying stem 41 is mounted to slide loosely endways in the bearing 42, sufficient space being left around the stem to permit the pressure of steam which flows through the valve to enter the space 43 in the head to act upon the relatively small exposed area of the upper diaphragm 34.

The lower end of this cylinder 30 is connected through pipe 44 down through the

pressure relief valve 45 and short pipe 46 into the usual ash pit of the furnace. This relief valve being provided with an endways slidable member 49 which is arranged to be moved from its seat by a cam pin 48 through the stem 49 when the door 11 of the furnace swings to open position on its hinge 50.

Water or other pressure may be supplied to this cylinder 30 from any convenient source through the supply pipe 51 and valve 52, the latter being just slightly opened so that the act of opening the furnace door for the purpose of stoking, opens the relief valve 45, will permit the water in the cylinder to run down into the ash pit and relieve the pressure in this cylinder 30 whereby when the pressure in this cylinder is released the pressure of steam in the upper chamber 53 of the valve 27 acting upon the closure member 54 forces it from its seat, the pressure then entering through the opening 55 acts upon the smaller diaphragm 34 through any water which may have accumulated in the space 43 forcing this diaphragm with the larger diaphragm downward permitting the valve closure member to be forced from its seat by the steam pressure thus permitting the steam to enter from the supply pipe 56 to pass through the control valve 27 a portion of which will pass through the pipe 26 to act upon the damper to open it permitting air to flow through the conduit 14 into the furnace and also permitting if desired another portion of this steam to flow through pipe 28 to and through the plurality of jet nozzles 12 to mix with the air from this conduit and assist in forcing it into the combustion chamber of the furnace.

After the stoking has been completed the fire door is closed permitting the pressure relief valve 45 to close under action of spring 57. Pressure is again built up in the pipe 44 by the water or other fluid which flows in through pipe 51. The amount of time required to build up the necessary pressure in cylinder 30 to close the control valve 29 being determined by the amount of opening of the valve 52, and after this pressure has been built up in this cylinder 30 sufficiently it acts upon the diaphragm 37 to force it with the diaphragm 34 upward to close the control valve 29 the further flow of steam therethrough is prevented until the relief valve 45 is again opened as above described by the opening of one of the stoking doors of the furnace.

My improved operating mechanism is extremely simple and practical in construction and effective in its operation and by its use the moving parts are greatly reduced and as all packing glands are eliminated no objectionable leakage can occur.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

- 10 1. In combination with a furnace, means connected with said furnace for introducing combustion-aiding fluid thereinto, a movable valve member controlling the flow of said fluid, a plurality of pressure-responsive elements operatively associated with said valve member, said elements being respectively subject to different pressures, and means whereby the manipulation of a furnace element is caused to control the action 15 of said pressures on said valve member to control admission of fluid to the furnace.
2. In combination with a furnace, means connected with the furnace for introducing combustion-aiding fluid thereinto, a valve 25 controlling the flow of said fluid, a plurality of pressure responsive elements of different exposed areas operatively associated with said valve, and means whereby the manipulation of a furnace element is caused to control the action of said pressures on said valve member to control admission of this fluid to the furnace.
3. In combination with a furnace, means 35 connected with the furnace for introducing combustion-aiding fluid thereinto, a valve subjected to inlet pressure of said fluid and arranged to control its flow, pressure-responsive elements of two different exposed areas to be operated by different pressures and operatively associated with said valve, and means operated by the manual manipulation 40 of a furnace element for effecting the valve closing pressure on one of said elements whereby said valve may be opened or closed to control the admission of fluid to the furnace.
4. In combination with a furnace, a damper 45 for controlling the flow of air to the furnace, a valve for controlling the flow of fluid for operating the damper, a plurality of auxiliary movable elements of different exposed areas operatively associated with said valve, and means controlled by manual manipulation of a furnace element for applying pressure to said different areas to open and close said valve to control the flow of said fluid to operate the damper.
5. In combination with a furnace, a damper 55 for controlling the flow of air to the furnace, a valve for controlling the flow of fluid for operating the damper, auxiliary movable elements of different exposed areas operatively associated with said valve, and means for applying the damper-operating pressure to one of said areas, a furnace door, and

means operated by the manipulation of said door for controlling an independent pressure to act upon other of said areas to open and close said valve to control the flow of said fluid to operate the damper.

6. In combination with a furnace, means for introducing combustion-aiding fluid thereinto, a valve for controlling the flow of this fluid, movable elements of different exposed areas operatively associated with said valve, both of said elements being effected by pressure of the supplying fluid to open the valve, a furnace door, and means controlled by the manipulating of the furnace door for controlling the supply of a second fluid pressure to act upon said elements to close the valve against the pressure of the supplying fluid.

7. The combination with a furnace, of a fluid jet for injecting air thereinto, a damper for controlling the flow of air to said jets, a valve, a plurality of movable elements of different operating areas actuated by two different actuating pressures operatively associated with said valve, and means controlled by the manipulation of a furnace part for releasing the pressure on one of said elements to permit the valve to open and to restore the pressure to close the valve.

8. The combination with a furnace, of a fluid jet for injecting air thereinto, a damper for controlling the flow of air to said jet, a valve for controlling the flow of fluid for operating said damper, a plurality of movable elements of different exposed areas arranged to be operated by two different pressures for controlling the operation of said valve, a furnace door, and means controlled by the manipulation of said door for controlling the valve-operating action of said pressures.

9. In combination with a furnace, means for supplying steam and air to the furnace, means whereby the flow of steam also assists the flow of air, a pressure valve for controlling the flow of the steam, movable elements of different exposed operating areas cooperating with said valve, means controlled by the manipulation of a furnace element for relieving the pressure on the larger of said elements to permit the supply fluid pressure to act upon said valve and the smaller element to permit said valve to open, said means being also arranged to restore the pressure on the larger element to act through the smaller element to close said valve.

10. In combination with a furnace, a steam-controlled damper for regulating the supply of air to the furnace, a steam jet to assist in forcing the air into the firepot above the fuel bed, a valve controlling the supply of steam to said damper-control and said jet, a plurality of cooperating valve opening and closing diaphragms, a furnace door, and means for releasing the closing pressure to

4
its diaphragm by opening said door permitting the pressure on the valve and the other diaphragm to open the valve.

11. In combination with a furnace, a passageway through which air is supplied thereto, a damper for controlling said passageway, a pressure-operated diaphragm for controlling the operation of said damper, and means including a pressure-control valve

and a diaphragm for operating said valve, 10
said valve-operating diaphragm being responsive to the action of pressure controlled by manual manipulation of a furnace element, whereby said damper diaphragm is 15
operated.

In testimony whereof I affix my signature.

ARTHUR W. PUDDINGTON.
